UNITED STATES PATENT OFFICE

RAYMOND A. REID, OF CEDAR RAPIDS, IOWA

SANDING MACHINE

Application filed February 19, 1927. Serial No. 169,642.

This invention relates to power-driven apparatus for sanding wood surfaces, the embodiment of the invention herein shown being more especially designed for finishing operations at a bench and manual movement of the machine.

The principal object of this invention is to provide a sanding machine with adequate means for catching the dust arising from the operation of the machine, and for arresting its escape into the air of the room in which the work is performed. This is a matter of prime importance in the operation of any sander, and presents difficulties that are not easily overcome.

The machine herein illustrated is of a special type, employing as the sanding drum the cylindrical shell which carries the field coils of an electrical motor. This is mounted in a suitable housing, the bottom of which serves as a surface guide, as will hereafter more particularly appear.

In the accompanying drawing, forming a part of this specification, Fig. 1 is a side elevation of a sander embodying the invention. Fig. 2 is a plan view of the same. Fig. 3 is a sectional view in the plane of the line 3—3 of Fig. 2. Fig. 4 is a sectional view of the same, looking toward the left, on the staggered line 4—4 of Fig. 3.

To a base 5 having a flat bottom, with an opening at 6 for a little of the periphery of the sanding roller 7, is connected, as by a hinge 8 at each side, a rear housing 9. This is recessed at 10 to receive the flattened ends of a shaft 11, which carries the armature of an electric motor. The details of the sanding roll are not important to this invention further than is herein illustrated, comprising the cylindrical field-coil shell 12 above referred to, and a pair of heads 13 secured thereto, as by screws 14. Over this is drawn a cushioning ring of felt, or the like, 15, and to this is suitably applied the sheet of abrasive 16. In operation the sanding roll, with the field coils attached, revolves on the fixed axis of the armature (not shown, except as to the shaft 11).

In front of the housing just described is mounted another housing 17, which serves

as an air outlet and dust screen. At its foot it has depending flanges 17^a fitting neatly inside the upstanding flanges 5^a of the base. At the top it is made to interlock with the rear housing by means of spring clips 18. The front and upper part of this dust-trap is pierced with holes 17^b for the escape of air. Inside of this is stretched a sheet of fabric of a suitable mesh to catch the dust, but permit the air to pass through, and inside of this is a protective screen of woven wire 19, holding the fabric in place.

The heads of the roller are provided with radial fan blades 13^a, which in the revolution of the roller in the direction indicated by the arrow tend to force the dust arising from the sanding of the surface below, back into the rear housing and thence over the roller into the considerable space between the roller and the dust-trap in front. Air for this current is admitted through openings 20 at each side of the housing. In practice this current of air and dust does not pass in a direct sheet from the bottom to the top of the roller and forward, but is deflected inwardly behind the roller and takes a forwardly and inwardly converging course, as indicated by the arrows in Fig. 2. The practical effect of this is that no dust or air escapes at the sides of the machine, and the only outlet for the air inflowing at the sides is through the screen of the dust-trap, as above described.

One of the difficult problems to solve has been to prevent leakage of air and dust between the joints of the housings and base, as thrown about by the rapidly revolving roller. To prevent this, at the sides, the inner cheeks of the dust-trap are lined with felt 21, the inner edges of the felt overlapping the rim of the roller and its felt, as indicated by the curved dotted line in Fig. 3, and as also shown in Fig. 4. This makes a dust-tight joint between the whole forward part of the roller and the sides of the dust-trap, with but little friction between the revolving roller and the fixed parts.

In the forward part of the base a pocket 22 is formed by the side walls and vertical

ribs 5^c and 5^d, and into this pocket falls the principal body of dust. The raising and lowering of the roller with respect to the base, to adjust it to its work, necessarily varies the gap at 23 to some extent. The felt liners of the cheeks protect the side gaps, and to shield the front gap 24 a rectangular sheet of felt 25 is folded at 25^a and securely clamped to the lower front edge of the dust-trap. This closes every avenue of escape for the dust, while allowing air to circulate freely. The accumulating dust must of course be emptied from time to time, but in the meantime the sander does its work with no scattering of dust in the room. A strip of felt 26 clamped to the upper, rear edge of the dust-trap seals the joint at the top of the machine. At the back of the rear housing the escape of dust at the joint 27, which varies slightly by the adjustment of the housing with respect to the base, is prevented by carrying the inwardly disposed rib 28 a little higher than the bottom edge of the housing, so that the ascending current of air and dust is carried past the joint without leakage.

Having thus described my invention, I claim:

1. In a sander, a supporting base, a circumferentially closed rear housing carried by the base, a housing forming a forward dust-trap joining the rear housing and base, and perforated for the escape of air, a forwardly disposed dust pocket formed in the base, and fibrous cheek-pieces lining the sides of the dust-trap and contacting closely with the ends of the roller in its arc of movement through said trap.

2. In a sander, a supporting base, opened for a part of a roller to project therethrough, a rear housing closed peripherally, a sanding roller revoluble therein, and provided with end fan-blades, and a dust-trap housing joining the rear housing and the base forwardly, pierced at the sides for admission of air to the fans, and forwardly for the escape of air, and screened against the escape of dust.

3. In a sander, a supporting base, opened for the projection of a peripheral arc of a roller, a rear housing mounted on the base, and closed peripherally, a dust-trap housing disposed forwardly thereof and over the base, with side openings to admit air and front openings to permit its escape, and a dust-retaining screen, a sanding roller revoluble in said housings and providing with end fan blades, and fibrous dust-proof linings for the dust-trap to close the joints between it and the rear housing and base, those at the sides over-lapping and lying close to one end of the roller in its arc of movement through the dust-trap.

4. In a sander, a base apertured for the projection of a roller rim, a rear housing carried by the base, a roller revoluble therein,

and a dust-trap joining the rear housing and the base forward of the roller, the front of the dust trap being perforated for the escape of air, screened to prevent the escape of dust, and fitted at the sides and joints with fibrous strips and sheets to prevent leakage of dust, those at the sides overlapping and closely engaging the portions of the roller ends disposed within said trap.

5. In a sander, a supporting base opened for a part of a roller to project therethrough, a housing structure having a roller revolubly mounted therein provided on its ends with fan-blades, said housing having openings for admitting air to the fan-blades at its sides and openings spaced therefrom for the escape of air.

In testimony whereof I affix my signature.

RAYMOND A. REID.
